Primary Examiner—Carol Rademaker*(74) Attorney, Agent, or Firm*—Cantor Colburn LLP**CLAIM**

The ornamental design for a bottle with oval fliptop, as shown and described.

DESCRIPTION

FIG. 1 is a front perspective view of the bottle with oval fliptop, showing my new design;

FIG. 2 is a top plan view thereof;

FIG. 3 is a front elevational view thereof;

FIG. 4 is a right side elevational view thereof, the left side being a mirror image;

FIG. 5 is a rear elevational view thereof; and,

FIG. 6 is a bottom plan view thereof.
